UNITED STATES PATENT OFFICE.

JULIUS OHMEN, OF NEW YORK, N. Y.

CASH-DRAWER.

SPECIFICATION forming part of Letters Patent No. 669,849, dated March 12, 1901.

Application filed June 19, 1900. Serial No. 20,850. (No model.)

To all whom it may concern:

Be it known that I, JULIUS OHMEN, a subject of the Emperor of Germany, and a resident of the city of New York, borough of Manhattan, in the county and State of New York, have invented a new and Improved Cash-Drawer, of which the following is a full, clear, and exact description.

The object of the invention is to provide a new and improved cash drawer or till which is simple and durable in construction and arranged to prevent unauthorized persons from obtaining access to the money upon pulling the drawer outward and at the same time give an alarm when said drawer is pulled out by the unauthorized person.

The invention consists of novel features and parts and combinations of the same, as will be fully described hereinafter and then pointed out in the claims.

A practical embodiment of the invention is represented in the accompanying drawings, forming a part of this specification, in which similar characters of reference indicate corresponding parts in all the views.

Figure 1 is a sectional side elevation of the improvement with parts of the casing broken out and with the drawer and money-receptacle in a closed position. Fig. 2 is a sectional side elevation of the improvement with the drawer partly pulled out and the money-receptacle in a locked innermost position. Fig. 3 is a sectional front view of the improvement on the line 3 3 in Fig. 1. Fig. 4 is a similar view of the same on the line 4 4 in Fig. 1. Fig. 5 is a sectional plan view of the same on the line 5 5 in Fig. 3, and Fig. 6 is an enlarged sectional side elevation of part of the alarm mechanism.

In a suitably-constructed casing A is mounted to slide a drawer B, in which is fitted loosely a money-receptacle C for receiving the money taken in by the operator. In the front end of the drawer B is mounted to turn a spindle D, carrying at its outer end a knob E, under control of the operator, for pulling out the drawer B and with it the receptacle C whenever it is desired to place money in said receptacle or to remove money therefrom.

On the spindle D, inside of the front of the drawer B, is secured an arm D', adapted to engage a loop or catch C', secured on the front

end of the receptacle C, so that when the spindle D is turned by the operator turning the knob E to engage the arm D' with said catch 55 then the receptacle C moves with the drawer outward or inward, according to the direction in which the knob E is moved. On the rear end of the receptacle C is secured a similar loop or catch C², adapted to be engaged by 60 a locking-arm F, attached to a disk G, having segmental slots G', engaged by screws or pins G², attached to a block G³, secured to or forming part of the casing A at the rear end thereof. 65

In the center of the disk G is formed a polygonal aperture G⁴, adapted to be engaged by a correspondingly-shaped reduced portion D² of the spindle D, near the rear end thereof, so that when the drawer B is in a closed position the said polygonal reduced portion engages the polygonal aperture G⁴ and turns the disk G, according to the direction in which the knob E is turned. The arms D' and F are so arranged relatively to each other that 75 when the arm D' moves in engagement with the catch C' then the disk G is turned and the arm F moves out of engagement with the catch C², and when the knob E is turned in an opposite direction the arm D' moves out of 80 engagement with the catch C', while the disk G is turned to move the arm F into engagement with the catch C². Thus when the arm D' is in engagement with the catch C' and the arm F is out of engagement with the catch C² 85 and the operator pulls on the knob E, then the drawer B moves outward and with it the money-receptacle C; but when the arm D' is out of engagement with the catch C' and the arm F is in engagement with the catch C² 90 and the operator pulls the knob E, then only the drawer B moves outward and without pulling the receptacle C along, as the latter is held within the casing in a locked lowermost position by the arm F engaging the catch 95 C². Thus the money-receptacle C remains concealed when the drawer B is opened by unauthorized persons, it being understood that only the operator in charge of the drawer knows how to turn the knob E to make proper engagement or disengagement with or from the arms D' and F and their catches C' and C². 100

When the receptacle C is in a locked innermost position and the drawer B is pulled out-

ward by an unauthorized person, then the said drawer actuates an alarm H, which, however, is not actuated, but is held in a locked position by the disk G at the time the arm F 5 is out of engagement with the catch C². The alarm H comprises a bell H' and a striker H² for the bell and secured on the escapement-shaft I of an escapement I', operating on an escapement-wheel I², secured on a shaft I³, connected by a train of gear-wheels with a shaft J, turned in one direction by a spring K and in an opposite direction by a pulley L, on which winds and unwinds a cord L', extending along one side of the casing, at the inside 15 thereof, over a pulley L², attached to this side of the casing, near the front end thereof, the return run of the cord being secured to the inner or rear end of the drawer B. Now when the drawer B is pushed inward the cord L' 20 turns the pulley L and shaft J to wind up the spring K and set the train of gear-wheels in motion, causing the escapement-wheel I² to actuate the escapement I' and striker H² and sound the alarm-bell H'. When the drawer 25 B is pulled in an outward direction, then the spring K rotates the shaft J in an opposite direction to again sound the alarm-bell H' and rotate the pulley L in an opposite direction to wind up the cord L'. Sounding of the 30 alarm now only takes place when the disk G is in such a position that its arm F is out of engagement with the catch C², and in order to control said alarm from the disk G a cord I⁴ is provided, secured at one end to the periphery of the disk G and extending over a 35 guide-pulley I⁵ to be attached to a hook I⁶ on the escapement I'. (See Fig. 6.) When the disk G is turned in the direction of the arrow a' (see Fig. 4) to move the arm F out of engagement with the catch C², then the disk G 40 pulls on the rope I⁴ and draws the escapement I' with one end down into a locking position with the teeth of the escapement-wheel I².

From the foregoing it will be seen that 45 when the operator has closed the drawer and turned the knob E to move the arm D' out of engagement with the catch C' and cause the arm F to move in engagement with the catch C² then an unauthorized person now pulling 50 on the knob E and drawing the drawer B open, without, however, taking the money-receptacle along, causes an alarm to be sounded, as now the alarm mechanism is set in motion. Thus the unauthorized person not only 55 cannot get hold of the money, but causes an alarm to be given whenever the drawer is opened by such unauthorized person.

Having thus fully described my invention, I claim as new and desire to secure by Letters 60 Patent—

1. A cash-drawer, comprising a drawer, a money-receptacle arranged to move either with the drawer when the latter is pulled out or pushed in, or to remain stationary during 65 such movement of the drawer, means carried by the drawer for locking the money-receptacle to the drawer, a locking device con-

trolled by said means, for holding the money-receptacle against movement by the drawer, and an alarm controlled by said means and 70 arranged to operate upon moving the drawer out without the money-receptacle.

2. A money-drawer, comprising a drawer, a money-receptacle therein, and two locking devices for said receptacle and both controlled by the drawer-knob, one locking device serving to lock the money-receptacle to the drawer and the other locking device serving to lock the receptacle to a stationary part, substantially as shown and described. 75

3. A casing, a drawer slidable therein, a money-receptacle in the drawer and provided at the front and rear ends with catches, a spindle carried by the drawer and mounted to turn therein and having an arm for engagement with the catch on the front of the money-receptacle, and a locking-arm mounted to turn to engage the rear catch on the money-receptacle, said locking-arm being controlled by said spindle, substantially as 85 shown and described. 90

4. A money-drawer, comprising a drawer, a money-receptacle therein, two locking devices for said receptacle and both controlled by the drawer-knob, one locking device serving to lock the money-receptacle to the drawer and the other locking device serving to lock the receptacle to a stationary part, an alarm actuated by the drawer, and means controlled by said last-mentioned locking device, for 95 throwing the alarm in or out of action according to the position of the locking devices, as set forth.

5. A casing, a drawer slidable therein, a money-receptacle in the drawer and provided at the front and rear ends with catches, a spindle carried by the drawer and mounted to turn therein and having an arm for engagement with the catch on the front of the money-receptacle, a locking-arm mounted to turn to 105 engage the rear catch on the money-receptacle, said locking-arm being controlled by said spindle, an alarm in said casing and actuated by said drawer, and means controlled by said locking-arm, for throwing the alarm in or out 110 of gear, substantially as shown and described. 115

6. The combination of a sliding drawer, a money-receptacle fitting loosely within the drawer and provided with a catch at each end, a knob-spindle mounted to turn in the drawer 120 and provided with an arm for engaging the catch on the front end of the money-receptacle, and a disk mounted to turn at the rear end of the drawer and with which the spindle engages to turn it, said disk being provided 125 with an arm for engaging the catch on the rear end of the money-receptacle, substantially as described.

7. The combination of a sliding drawer, a money-receptacle fitting loosely in the drawer 130 and provided with a catch at each end, a knob-spindle mounted to turn in the drawer and provided with an arm for engaging the catch on the front end of the money-receptacle and

with a polygonal inner end, and a disk mounted to turn at the rear end of the drawer and provided with a polygonal center opening to receive the inner end of the spindle and with 5 an arm projecting therefrom and adapted to engage the catch on the rear end of the money-receptacle, substantially as described.

8. The combination of a drawer, a money-receptacle fitting loosely therein and having 10 a catch at its rear end, an arm mounted to turn and adapted to engage the said catch, a knob-spindle for operating the arm, a bell, a striker, means for operating the striker and containing an escapement and escapement- 15 wheel, and a connection between the escapement and the swinging arm, substantially as described.

9. The combination of a drawer, a money-receptacle fitting loosely in the drawer, and

having a catch at each end, a knob-spindle 20 provided with an arm for engaging the catch on the front end of the money-receptacle, a disk mounted to turn at the rear end of the drawer and with which the spindle engages to turn it, said disk being provided with an 25 arm for engaging the catch on the rear end of the money-receptacle, a bell, a striker, means for operating the striker, and containing an escapement and escapement-wheel, and a flexible connection between the escapement 30 and the said disk, substantially as described.

In testimony whereof I have signed my name to this specification in the presence of two subscribing witnesses.
